UNITED STATES PATENT OFFICE.

FRANCIS BRUCKER, OF LANSING, MICHIGAN.

SPRING-HINGE.

1,123,478.

Specification of Letters Patent.

Patented Jan. 5, 1915.

Application filed January 16, 1914. Serial No. 812,560.

To all whom it may concern:

Be it known that I, FRANCIS BRUCKER, a citizen of the United States, residing at Lansing, Michigan, have invented certain new and useful Improvements in Spring-Hinges, of which the following is a specification.

My present invention relates to improvements in double acting spring hinges for doors and has, among others, for its objects to provide various improved details of construction of advantage in the operation of the hinge.

The invention therefore includes the novel features of construction and arrangement and combination of parts hereinafter described and particularly defined by the appended claims.

An embodiment of my invention is illustrated in the accompanying drawings, in which—

Figure 1 is a side elevation of a double acting spring hinge with the casing in section; Fig. 2 is a sectional plan.

Referring by reference characters to this drawing, the door is indicated at 2 and the floor or base at 3. The frame which holds the working parts of the hinge comprises a bar 4 having one end turned downwardly, as indicated at 4^a, and the other end turned upwardly at an angle of approximately 45°, the latter being provided with holes for the reception of screws for fastening the bar securely to the door. The spring 5 has one end adapted to adjustably bear against the turned down end 4^a, and I provide a double adjustment at this point, one longitudinal for varying the tension of the spring and the other lateral for bringing the door into exact alinement with the door casing. The adjustment of the tension is effected by means of a nut 6 threaded on a screw 7 secured to said end 4^a. The lateral adjustment is secured by having the reduced end 45 of said screw passed through a laterally elongated slot 4^c in said end 4^a, and held in position by a clamp nut 8.

The hinge post 9 is of improved construction, and is made integral with the base

plate 10. This latter plate has formed integral therewith a flat-topped circular boss 10^a, upon the upper face of which rests the lower face of the plunger 11. This plunger has a shank 11^a which extends for a suitable distance within the spring, and has side recessed portions 11^b designed to bear against curved wings 9^a of the post 9. The post preferably has a bracing web 9^b. The lower face of the head 11 of the plunger rests on the upper face of the boss 10^a, while its upper face bears against the under side of the bar 4. In order to reduce friction as the door swings, I provide on the top of the post a ball carrier 12 having a ball race for balls which bear against the under side of the bar 4. The hinge is held to the base plate by a hinge pin 13 which has its head countersunk in the boss 10^a, and its upper end provided with a clamping nut 13^a. The sides of the spring are incased by ornamental side plates 24 which overlap each other at the rear. As will be seen from the drawings the plates cover the turned up end of the frame.

Having thus described my invention what I claim is:

1. In a spring hinge, a frame open at its lower side, a post with means for connecting it to the floor and having an enlarged base or boss with a flat upper surface, a pivot pin passing through the post and frame, and a spring pressed shank guided between the boss and frame, and bearing against the post.

2. A spring hinge comprising a stationary post, a frame pivotally connected thereto, a plunger bearing against the post, a spring bearing against the plunger at one end and against the frame at the other end, and means independent of the plunger for effecting lateral adjustment of said other end of the spring.

In testimony whereof I affix my signature in presence of two witnesses.

FRANCIS BRUCKER.
